UNITED STATES PATENT OFFICE.

LUTHER G. BILLINGS, OF CLIFTON, NEW YORK.

DESIGN FOR A BICYCLE-FRAME.

SPECIFICATION forming part of Design No. 26,179, dated October 13, 1896.

Application filed August 28, 1896. Serial No. 604,224. Term of patent 14 years.

To all whom it may concern:

Be it known that I, LUTHER G. BILLINGS, a citizen of the United States, residing at Clifton, in the county of Richmond and State of New York, have invented and produced a certain new and original Design for a Frame for a Bicycle, of which the following is a specification, reference being had to the accompanying drawing, forming part thereof, and showing in side elevation a frame embodying my design.

The leading features of the design are the inclined straight front member, the circular loop at the rear, and the reversed curved member joining the one to the other. Within the circular loop is a smaller concentric circular portion of the frame attached to the loop by a plurality of braces equally spaced, the one at the rear being straight and the others serpentine. A slender portion of the frame extends forward tangentially from the periphery of the loop to a point on the under side of the reversed curved member near its mid-length, and a similar but heavier portion extends tangentially from a point on the opposite side of the loop in an upwardly-inclined direction to the upper end of a support springing from the reversed curved member and extending upward therefrom in a grace-

ful compound curve. The reversed curved member and the upper tangential portion are double. The lower part of the first joins the upright member at a sharp angle and flows smoothly into the loop at the rear while the upper part curves into the upright member and at the rear joins the loop by a short upward curve. The upper part of the tangential member is straight throughout, the lower part following the same line during the greater portion of its length and then curving downward to join the loop.

The arrangement of combined straight and curved members shown in this design produces a pleasing effect of strength and lightness with grace and beauty particularly desirable in constructions of this character and purpose.

I claim—

The design for a frame for a bicycle, substantially as herein shown and described.

In testimony that I claim the invention above set forth I affix my signature in presence of two witnesses.

LUTHER G. BILLINGS.
